U.S. Appl. No. 10/919,494, filed Aug. 17, 2004, Stein.

Primary Examiner—Ralf Seifert

(74) Attorney, Agent, or Firm—Jones Day; Brett Lovejoy

(57) **CLAIM**

The ornamental design for a key locator, as shown and described.

DESCRIPTION

FIG. 1 is a front right perspective view of an ornamental design for a key locator according to the present invention; FIG. 2 is a front elevational view thereof; FIG. 3 is a back elevational view thereof; FIG. 4 is a right side elevational view thereof; FIG. 5 is a top plan view thereof; and, FIG. 6 is a bottom plan view thereof.

All portions shown in broken lines are environmental and illustrative only, and form no part of the claimed design.
